William McNair Inventor

Lacey & Lacey, Attorneys

UNITED STATES PATENT OFFICE.

WILLIAM McNAIR, OF SAN ANTONIO, TEXAS.

GOLF CLUB.

Application filed October 1, 1926. Serial No. 138,935.

This invention relates to golf clubs and has special reference to putters, the object of the invention being to provide an efficient club of such construction that the head may be easily adjusted for use by either a right handed or a left handed player and may be also adjusted quickly and easily to suit any given lie. The invention provides means whereby the shaft may be disposed at various angles to the head and may also be shifted longitudinally of the head to suit the taste or fancy of any player and will be effectually held in any set position so that the club may be used freely without the elements being apt to be disassembled. These stated objects, and other objects which will incidentally appear in the course of the following description, are attained in such a device as is illustrated in the accompanying drawing, and the invention resides in certain novel features which will be particularly pointed out in the appended claims.

In the drawing:

Figure 1 is a perspective view of a golf club embodying the invention, the greater portion of the shaft being broken away;

Fig. 2 is a central vertical longitudinal section of the same;

Fig. 3 is a transverse section, and

Fig. 4 is a detail section on the line 4—4 of Fig. 3.

The shaft 1 is of the usual form and is constructed of wood or other preferred material, a sleeve 2 being secured to the lower end 35 of the shaft and provided with an internally threaded bore 3. The head 4 is a hollow metal casting which is preferably of the form now generally employed for putters, the striking face 5 being flat and slightly 40 inclined. A cover 6 is secured upon the hollow head 4 and corresponds thereto in shape so that the edges of the cover will be flush with the corresponding surfaces of the body of the head when the parts are assembled. The cover is provided on its upper 45 side with a longitudinally extending rib 7 having transverse teeth 8 formed in its upper surface and having a central longitudinal slot 9 terminating short of its ends. On the 50 under side of the cover at the sides of the slot 9 are longitudinal ribs 10 having teeth 11 formed transversely in their lower edges, it being noted upon reference to Fig. 3 that the opposed surfaces of these ribs are flush 55 with and form continuations of the walls of the slot 9. Threaded into the sleeve 2 is a

shank 12 which is flattened at its lower end portion, as indicated at 13, whereby it may be inserted upwardly through the slot 9 of the cover before the cover is placed upon the hollow head and have its shank engaged in the threaded bore of the sleeve 2. The lower end of the shank is constructed with a cross head 14 extending to both sides of the shank and having its laterally extending terminals tapered upwardly to form teeth 15 adapted to engage between the teeth 11 on the ribs 10, it being noted upon reference to Fig. 2 that the taper of the teeth 15 is sharper than the taper of the teeth 11 whereby, under certain conditions, the shank with its crosshead may be rocked upon the ribs 10. Interposed between the rib 7 and the lower end of the sleeve 2 is a wedge 75 or clamping member 16 having a lower face adapted to rest squarely upon the ribs 7 and provided with transverse teeth 17 mating with the teeth 8, as clearly shown in Figs. 1 and 2. Rising from the lower portion of this wedge or clamping member is an inclined hub 18, the bore 19 of which is considerably greater in diameter than the diameter of the shank 12 so that the said hub may surround the shank and at the same time permit a limited relative angular movement of the shank. The lower end of the sleeve 2 rests upon the upper end of the hub 18 and to avoid wear upon the opposed surfaces, the upper edge of the hub and the lower end of the sleeve are both given an 80 arcuate formation, as indicated at 20 in Figs. 2 and 3.

To assemble the parts, the shank 12 is inserted upwardly through the slot 9 in the cover 6 and the wedge 16 is then fitted 95 against the top of the cover with its hub housing the upper portion of the shank. The sleeve 2 is then engaged with the projecting threaded end of the shank and is turned 100 home against the wedge sufficiently to hold the parts in their assembled relation. The cover may then be placed upon the head of the club and secured by screws, indicated at 21, in an obvious manner. If the parts are assembled in the exact position that the player desires, the shaft with the sleeve 2 may be rotated so as to draw the teeth 15 of the head 14 into close engagement with the ribs 10 and to clamp the wedge 16 upon the cover. The interengaging relation of the teeth 11 110 and 15 and the teeth 8 and 17 will then very effectually prevent shifting of the shaft.

longitudinally of the head while the clamping action of the crosshead 14 and the wedge upon the opposite surfaces of the cover will positively prevent detachment of the head from the shaft. Obviously, the parts may be assembled so that the shaft will be at the center of the head or in front of or behind the center as may be preferred, and in order to reverse the club so that it may be used by a left handed player all that needs to be done is to loosen the sleeve 2 to such a degree that the clamp 16 may be withdrawn from the teeth 8 and the crosshead 14 lowered sufficiently to clear the teeth 11, whereupon the head may be swung in a horizontal plane between the clamp and the crosshead so that its striking face 5 will be brought to the opposite side of the wedge and the crosshead, the parts being then tightened in the new position. The shaft may be set at any desired angle, within limits, so that it may approach more closely to the vertical or to the horizontal as may be desired to suit the fancies of the player or to adapt the club to any particular lie. To accomplish this result, the sleeve 20 is loosened so that it may move freely across the upper end of the wedge 16, whereupon the shaft and the shank 12 may be rocked about the edge of the tooth 15 as a center, as indicated by the dotted lines in Fig. 2, the sleeve 2 being then rotated about the threaded portion of the shank 12 to again clamp the parts together.

35 My device is exceedingly simple in construction and may be very easily adjusted to cover a wide range of conditions in play.

Having thus described my invention, I claim:

40 1. The combination of a head, a shaft, and means adjustably connecting the shaft with the head whereby the shaft may be set at a selected point in the length of the head.

2. The combination of a head, a shaft, a shank connected with the shaft and engage-

able internally with the head, and an intermediate member disposed between the head and the shank, the shank and shaft being relatively longitudinally adjustable whereby to clamp the shank and the intermediate member to the head. 45

3. The combination of a head, a shaft, a shank connected with the shaft and engaged with the interior of the head, and a clamping member disposed between the head and the shaft and encircling the shank and having a bore greater than the diameter of the shank whereby to permit angular adjustment of the shank and the shaft.

4. The combination of a hollow head having a longitudinal slot in its top and provided with transverse teeth on the upper and lower surfaces of its top, a shaft, a shank engaged with the shaft and passing through the longitudinal slot in the head and provided at its lower end with a member adapted to engage with the teeth on the under side of the top of the head, and an intermediate member disposed between the shaft and the head around the shank and provided in its lower side with teeth engaging the teeth on the upper surface of the top of the head. 60 65 70

5. The combination of a hollow head having a longitudinal slot in its top and provided internally and externally with transverse teeth, a shaft, a shank playing in the longitudinal slot of the head and provided at its lower end with a cross-head tapered upwardly to engage the internal teeth of the head, and an intermediate member provided on its under surface with teeth engaging the external teeth of the head and having an inclined bore receiving the shank end of appreciably greater diameter than the shank, the shank having a threaded engagement with the shaft. 80

In testimony whereof I affix my signature.

WILLIAM McNAIR. [L. s.]
